UNITED STATES PATENT OFFICE.

ROSCOE F. WARREN, OF LOS ANGELES, CALIFORNIA.

DESIGN FOR A COMBINATION HOLSTER AND BELT.

Application filed December 15, 1927. Serial No. 24,493. Term of patent 14 years.

To all whom it may concern:

Be it known that I, ROSCOE F. WARREN, a citizen of the United States, residing at Los Angeles, in the county of Los Angeles and State of California, have invented a new, original, and ornamental Design for a Combination Holster and Belt, of which the following is a specification, reference being had to the accompanying drawing, forming part thereof.

I claim:

The ornamental design for a combination holster and belt, as shown.

ROSCOE F. WARREN.
